UNITED STATES PATENT OFFICE.

HOWARD A. HAMACHER, OF RICHMOND, MISSOURI.

LID-SUPPORT.

1,372,503.

Specification of Letters Patent. Patented Mar. 22, 1921.

Application filed July 23, 1920. Serial No. 398,386.

To all whom it may concern:

Be it known that I, HOWARD A. HAMACHER, a citizen of the United States of America, residing at Richmond, in the county of Ray and State of Missouri, have invented new and useful Improvements in Lid-Supports, of which the following is a specification.

This invention relates to lid supporting devices for holding a lid in open position and has for its object the provision of a novel device for holding open the lid or cover of a talking machine cabinet, the device automatically operating to hold the lid when the lid is merely raised and the device furthermore permitting return of the lid to closed position when the lid is merely raised somewhat above its normal open position.

An additional object is the provision of a device of this character which will be very simple and inexpensive in manufacture, easily applied, highly efficient and durable in service, and a general improvement in the art.

With the above and other objects and advantages in view, the invention consists in the details of construction to be hereinafter more fully described and claimed, and illustrated in the accompanying drawings in which—

Figure 1 is a fragmentary sectional view through a talking machine cabinet and its cover, showing my device applied thereto and showing the cover closed,

Fig. 2 is a similar view showing the cover in open position,

Fig. 3 is a similar view showing the cover raised excessively to release the holding means,

Fig. 4 is a similar view showing the holding means fully released,

Fig. 5 is an enlarged detail view of the lid carried arm,

Fig. 6 is a detail view of the element carried by the cabinet, and

Fig. 7 is an edge view of the lid carried arm.

Referring more particularly to the drawings, the letter A designates a talking machine cabinet and B designates an ordinary hinged cover thereof. Mounted in the top of the cabinet is a plate 10 having a longitudinal slot 11 into which projects a lug 12.

Carried by the lid B and pivotally mounted within a bifurcated bracket 13, is an arm

14 which is slidable through the slot 11 in the plate 10 and which is disposed between one end of the slot and the lug 12 so that it will gravitationally bear against the lug 12 at all times. At one side the arm 14 is recessed, as shown at 15, and this recess has a long curved wall 16 which merges into a notch 17 which provides the retaining shoulder 18. Pivotedly mounted upon the arm 14, as shown at 19, is a movable cam-like member 20 which is so pivoted that its center of gravity will be such that its lower end will normally, that is when the cover B is closed, engage at the juncture of the curved wall 16 with the straight edge of the arm. This movable member 20 has a curved edge 21 spaced from the curved wall 16 of the recess to provide a passage and when the member 20 is in normal position, as shown in Fig. 1, its upper end will be disposed in spaced relation to the shoulder 18 of the arm.

Assuming that the cover B is closed, as shown in Fig. 1, when the operator lifts the cover the arm 14 will ride within the slot 11 with the lug 12 against the lower edge of the arm. During this movement of the arm, when the upper end of the movable member 20 engages the lug 12, the lug 12 will be deflected into the space between the upper end of the member 20 and the shoulder 18, or in other words, the arm 14 will drop so that the space between the shoulder 18 and the member 20 will pass over the lug 12 whereupon the lug 12 will seat within the notch 17 when further elevating of the cover B is discontinued. The cover will then be effectively supported in elevated position without any danger of dropping.

When it is desired to close the cover, the operator grasps it and moves it still farther upwardly whereupon the movement of the arm 14 will cause the lug 12 to ride along the space between the curved edge 21 of the member 20 and the curved wall 16 of the recess 15 until the lug 12 passes beyond the member 20 and against the lower straight edge of the arm 14. As soon as the lug 12 passes from between the curved wall of the recess and the curved edge of the member 20, the member 20 will gravitate into the position shown in Fig. 4 with the lower end engaging the juncture of the curved wall 16 with the lower straight edge. The operator then allows the cover B to descend whereupon the lug 12 will ride idly over the outer straight edge of the member

20 as the arm 14 returns to normal position. The parts are then in proper position for a repeated operation.

From the foregoing description and a study of the drawings it will be apparent that I have thus provided a lid support which will automatically operate to hold the lid in open position without touching the device and which will also operate to permit the lid or cover to be reclosed also without any necessity for manual manipulation. It will be noted that the device is very simple and that there is only one moving part and that it will be consequently inexpensive and 15 easy to install.

While I have shown and described the preferred embodiment of my invention, it is of course to be understood that I reserve the right to make such changes in the form, 20 construction, and arrangement of parts as will not depart from the spirit of the invention or the scope of the subjoined claims.

Having thus described my invention, I claim:

25 1. In combination with a casing and its hinged cover, a cover supporting device comprising a lug carried by the casing, an arm pivotally connected with and depending from the cover and having its lower edge bearing against said lug, said arm being recessed at one side to define a curved wall and a notch providing a retaining shoulder, and a movable member pivoted within said recess and having a curved edge spaced 30 from the curved wall thereof, and said mem-

ber being so pivoted that its lower end will constitute in effect, a weight causing said movable member to assume a position with its lower end engaging against the juncture of said curved wall with the straight edge 40 of the arm and its upper end in spaced relation to said shoulder to provide a passage into which said lug may pass.

2. In combination with a casing and its hinged cover, a cover supporting device comprising a lug carried by the casing, an arm pivotally connected with and depending from the cover and having its lower edge bearing against said lug, said arm being recessed at said lower edge to define a curved 50 wall and a retaining shoulder, and a movable member pivoted within said recess and engageable by said lug.

3. In combination with a casing and its hinged cover, a cover supporting device comprising a lug carried by the casing, an arm pivotally connected with and depending from the cover and having its lower edge bearing against said lug, said arm being recessed at said lower edge to define a curved 55 wall and a retaining shoulder, and a movable member pivoted within said recess and engageable by said lug, said movable member being eccentrically pivoted whereby its lower end will normally engage against said 60 curved wall at its juncture with the lower edge of said arm.

In testimony whereof I affix my signature.

HOWARD A. HAMACHER.
